UNITED STATES PATENT OFFICE.

FRANK E. LIVERANCE, JR., OF WYOMING PARK, MICHIGAN, ASSIGNOR TO THE
MCCASKEY REGISTER COMPANY, (INCORPORATED IN 1914,) OF ALLIANCE,
OHIO, A CORPORATION OF OHIO.

FILING APPLIANCE.

1,273,243.

Specification of Letters Patent. Patented July 23, 1918.

Application filed August 12, 1915. Serial No. 45,482.

To all whom it may concern:

Be it known that I, FRANK E. LIVERANCE, Jr., a citizen of the United States of America, residing at Wyoming Park, in the county of Kent and State of Michigan, have invented certain new and useful Improvements in Filing Appliances; and I do hereby declare the following to be a full, clear, and exact description of the invention, such as will enable others skilled in the art to which it appertains to make and use the same.

This invention relates to filing leaf constructions adapted to be located in a casing in upright or horizontal position and hinged together at their lower ends that they may be moved from one position to the other and vice versa. It is the object and purpose of this invention to provide a new and improved construction relating to the hinging means through which the leaves are connected together adjacent their lower ends. The invention consists in novel constructions and arrangement of parts as will fully appear from the description and the appended claims, reference being had to the accompanying drawing, in which;

Figure 1 is a side elevation of a plurality of leaves connected together adjacent their ends by use of my invention.

Fig. 2 is a perspective view of the hingedly connected sockets, a plurality of which are made use of in embodying the invention; and

Fig. 3 is a perspective view showing the leaf construction and the connection of said sockets to the filing leaves.

Like reference numerals refer to like parts throughout the several views of the drawing.

In the embodiment of the invention shown, a plurality of leaves are provided formed preferably from sheet metal and comprising a body 1 which, along its upper edge, is fashioned to make the rib 2. At its lower edge the metal is turned to form a tube 3 preferably square in cross section though other shapes may be used quite as well. A plurality of vertical spacing bars 4 are connected to the front and rear of the leaf in the usual manner to divide the leaf into a plurality of compartments to contain bills or like articles, it being un-

derstood that the usual clips for retaining the bills may be applied to the body 55 of each leaf at the front and rear sides thereof.

At a number of points in the length of the tubular portion 3 of each leaf parts are cut away leaving openings as indicated at 5. As shown in Fig. 3, these openings occur at three points in the width of the leaf though preferably in practice I prefer to provide the openings adjacent each end of the tubular portion only. In the opening 65 left a sleeve having a cross section identical with and substantially the same size as the cross section of the tube 3 is located, it consisting of upper and lower members 6 and 7 formed with pintle engaging members 8 70 that extend forward from the sleeve. The members 8 are spaced apart and are adapted to receive between them a pintle receiving member 8^a which is formed at the rear of and connected to each sleeve. A pintle 75 9 passing through said members 8 and 8^a hinges the adjacent sleeve members together.

With one of these sleeves placed in each of the openings 5 and in alignment with 80 the tubular portion 3 of a leaf, a bar 10 is inserted through the part 3 and the sleeves serving in this manner to connect the leaf and sleeves together. It is of course understood that the bar 10 is of such cross 85 section that it fits snugly within the tube 3 and the sleeves. If desired, after the leaf and sleeves have thus been assembled the bar may be rigidly secured in place or, preferably, it may be left so as to be removable 90 if at any time this becomes desirable.

The rear leaf will be connected with sleeve members 11 similar in all respects to the members heretofore as connected with the intermediate leaves except that no rearwardly extending pintle receiving member 95 8^a will be secured thereto, while the front leaf will have sleeve members similar to the intermediate sleeves except that no forwardly projecting pintle receiving members 100 8 will be connected therewith. If desired, the bar 10 associated with the front leaf may at each end have an outwardly extending pivot 12 adapting it to be pivotally connected to any suitable support in the same 105 manner that the front leaves of leaf packs

of this character are now connected to their supports.

This construction of leaf can be very economically produced. The tube 3 at the lower ends serves as a side for the bill receiving compartments and is insured against bending or other malformation through the rigid bar 10 inserted therethrough. The assembly of a pack of leaves by this invention is very quickly and easily accomplished and if any leaf should become injured or in any manner rendered unfit for service it can be very easily removed by merely removing the bar 10 thereof and a new one provided in its place.

I claim:

1. In combination, a plurality of filing leaves, each having a tubular lower end with parts thereof removed at a number of points in the width of the leaf, a plurality of devices hinged together, each device including a sleeve of substantially the same cross-section as and located in alignment with the tubular portion of a leaf, and a bar inserted through said tubular portion of each leaf and said hinged device associated with the leaf, substantially as described.
2. In combination, a plurality of filing leaves located one back of another, each having a tubular lower end with parts thereof removed at a number of points in the width of the leaf, devices each including a sleeve having a cross-section substantially the same as and located in alignment with said tubular portions of each leaf at the openings therein, a bar extending through each tubular portion and the said devices

associated therewith, and means hinging together the devices on adjacent leaves.

3. In combination, a plurality of filing leaves located one back of another, and each formed at its lower end with a tubular portion, a bar extending through said tubular portion, hinged devices connected to the bar between its ends and interlocked between the bar and the leaf, and means for pivotally connecting the hinging devices on one leaf to the similar devices on adjacent leaves.

4. A filing leaf including a body of sheet metal formed at its lower end into a tube, and having parts removed at a plurality of points in the length of the tube, sleeves located in the openings left by said removed portions, a bar extending through the tube and sleeves, and pintle receiving members formed on the sleeves, substantially as described.

5. A filing leaf including a body of sheet metal formed at its lower end into a tube, and having parts removed at a plurality of points in the length of the tube, sleeves located in the openings made at such removed portions, a bar extending through the tube and sleeves, and means on the sleeves whereby they may be pivotally connected to similar sleeves on similarly formed leaves, substantially as described.

In testimony whereof I affix my signature in presence of two witnesses.

FRANK E. LIVERANCE, Jr.
